UNITED STATES PATENT OFFICE

RONALD A. McCANN, OF SWISSVALE, PENNSYLVANIA, ASSIGNOR TO THE UNION SWITCH & SIGNAL COMPANY, OF SWISSVALE, PENNSYLVANIA, A CORPORATION OF PENNSYLVANIA

RAILWAY TRAFFIC CONTROLLING APPARATUS

Application filed September 11, 1928. Serial No. 305,176.

My invention relates to railway traffic controlling apparatus, and particularly to apparatus of the type comprising apparatus located on a vehicle and arranged to co-operate with means located in the trackway for controlling traffic governing mechanism in the trackway or on the vehicle.

I will describe several forms of apparatus embodying my invention, and will then point out the novel features thereof in claims.

In the accompanying drawings, Fig. 1 is a diagrammatic view showing one form of apparatus for transmitting a control impulse from the vehicle to the trackway, and embodying my invention. Fig. 2 is a diagrammatic view illustrating an application of my invention to the control of tripping devices in the trackway. Fig. 3 is a diagrammatic view illustrating an application of my invention to the control of a railway switch from a moving vehicle. Fig. 4 is a view, partly diagrammatic, illustrating an application of my invention for controlling vehicle carried governing means from the trackway.

Similar reference characters refer to similar parts in each of the several views.

Referring first to Fig. 1, the reference characters 11 designate a plurality of nozzles which are at times supplied with fluid pressure for controlling a relay device L. For example the nozzles 11 may be mounted on a railway vehicle, and the relay device L may be located in the trackway adjacent the path of travel of the nozzles. As here shown the nozzles 11 are connected, through pipe 10, a manually operable valve V, and pipe 9, with an auxiliary reservoir A^R which is charged with fluid pressure from a main reservoir M^R through pipe 7. The main reservoir M^R is constantly connected with a source of fluid pressure, not shown in the drawings, through pipe 7^a. The valve V normally occupies the position shown in the drawings, so that reservoir A^R is normally disconnected from nozzles 11, but when the valve is operated fluid from reservoir A^R is supplied to pipe 10, so that a jet of the fluid escapes from each of the nozzles 11. A restricted orifice 8 in pipe 7 prevents fluid from escaping from reservoir M^R at a rate which is

greater than the rate at which fluid is supplied to the main reservoir M^R through pipe 7^a.

The jets delivered by the nozzles 11 control a relay device L, which, in the form here shown, comprises a cylindrical housing 17 located in the trackway adjacent the path of travel of nozzles 11, and having a funnel shaped member 16 attached to its upper end. Located in the housing 17 is a hinged diaphragm 13, which is operatively connected with two contacts 14 and 15 in any suitable manner, such as, by an operating rod 18. A spring 19, attached to the lower end of rod 18, holds the diaphragm in the normal position in which it is illustrated in the drawings. If a jet of air having sufficient pressure is directed toward diaphragm 13, the spring 19 is compressed, and contact 15 is closed while contact 14 is opened. In some instances it may be desirable to insert baffle plates j, k, and n in the member 16 to direct the air more efficiently toward the diaphragm 13. With the apparatus thus far described, if the valve V on the train is operated as the train passes the relay device L, the diaphragm 13 is deflected to operate contacts 14 and 15. Relay devices similar to device L just described may be utilized to control trackway governing apparatus as shown in Fig. 2.

Referring now to Fig. 2, the reference characters 1 and 1^a designate the track rails of a stretch of railway track over which traffic normally moves in the direction indicated by the arrow. These rails are divided, by means of insulated joints 2, into a plurality of successive track sections A—B, B—C, C—D, D—E, etc. Each such track section is provided with a track transformer, designated by the reference character F with an exponent corresponding to the location, and having its secondary 3 connected across the rails adjacent the exit end of the section. The primary 4 of each such track transformer F is constantly supplied with alternating current from a suitable source of energy such as a generator G, over line wires 5 and 6. Each section is also provided with a track relay, designated by the reference

100

character H with an exponent corresponding to the location, and connected across the rails adjacent the entrance end of the section. Thus it is clear that each section is provided with a track circuit which includes a secondary 3 of a transformer F, a track relay H, and the rails of the section in series.

Located adjacent the entrance end of each section is a signal designated by the reference character J with an exponent corresponding to the location. Each signal J is provided with an upper or "home" semaphore blade 21, and a lower or "distant" semaphore blade 20. Each of the blades 20 and 21 is capable of assuming either a proceed or a stop position. When both blades are in the stop position, the signal indicates "stop"; when the home blade is in the proceed position and the distant blade is in the stop position, the signal indicates "caution"; and when both blades are in the proceed position, the signal indicates "proceed". Each home blade controls three signal circuit controllers N, O, and P, and each distant blade controls a circuit controller Q in the usual manner.

Located in the trackway in rear of each signal J is a tripper arm designated by the reference character M with an exponent corresponding to the location. Each tripper arm M is biased to an effective position (see M^B), but may be moved to an ineffective position (see M^A) by means of the usual operating mechanism not shown in the drawings. Each tripper arm M also comprises a circuit controller S which is arranged to be closed when the arm occupies its ineffective position but to be open when the arm occupies its effective position. The tripper arms M are suitable for co-operation with vehicle carried apparatus including a part which will be engaged by the tripper arm in its effective position to give a stop indication on board the vehicle. If the tripper arm is in its ineffective position when the vehicle passes, the tripper arm will have no effect upon the vehicle carried means. This vehicle carried apparatus forms no part of my present invention and is not shown in the drawings.

Each section is provided with a relay device L similar to the device L shown in Fig. 1. Each section is further provided with a relay designated by the reference character K with an exponent corresponding to the location, and with a marker light 39. Each marker light 39 is located in the trackway adjacent the associated tripper arm M and informs the operator of the train of the location of the tripper arm. Furthermore, when the marker light is lighted, the operator is informed that the tripper arm occupies its effective position.

Referring particularly to section A-B, the distant blade 20 of signal J^A is provided with a circuit which passes from battery R^C

through wires 24, 34, and 35, circuit controller O^C controlled by home blade 21 of signal J^C, wire 25, circuit controller N^B controlled by home blade 21 of signal J^B, wire 26, front contact 37-37^a of relay H^B, wire 27, front contact 38-38^a of relay H^A, wire 28, operating mechanism of distant blade 20 of signal J^A, wires 29 and 30, contact 14 of device L^A, wires 31, 32, and 33, common wire 36, and wires 40 and 41 back to battery R^C. This circuit is closed when relays H^A and H^B are energized, and when signals J^B and J^C both indicate proceed or caution, which condition exists only when sections A-B, B-C, and C-D, are all unoccupied.

The home blade 21 of signal J^A is provided with a circuit which passes from battery R^A, through wires 42, 43, and 69, front contact 46 of relay H^A, wire 44, operating mechanism of home blade 21 of signal J^A, wires 45 and 30, contact 14 of device L^A, wires 31, 32, and 33, common wire 36, and wires 47 and 48 back to battery R^A. This circuit is closed except when a vehicle occupies section A-B to de-energize relay H^A, or when contact 14 of device L^A is open. It will be apparent, therefore, that when sections A-B, B-C, and C-D are all unoccupied, signal J^A indicates proceed when either section B-C or C-D is occupied, signal J^A indicates caution; and when section A-B is occupied, signal J^A indicates stop. Each of the remaining signals J is provided with circuits similar to those described for signal J^A.

Still referring particularly to section A-B, relay K^A is provided with a pick-up circuit which passes from battery R^A, through wires 42, 43, and 49, contact 15 of device L^A, wires 50 and 58, winding of relay K^A, wire 73, common wire 36, and wires 47 and 48 back to battery R^A. In order to pick up relay K^A, therefore, it is necessary to operate device L^A. When relay K^A is picked up, and when signal J^A indicates caution or proceed, so that circuit controller P^A is closed, relay K^A is energized over a stick circuit which passes from battery R^A, through wires 51, 52, and 58, circuit controller P^A controlled by home blade 21 of signal J^A, wires 66 and 74, front contact 56 of relay K^A, wires 57 and 58, winding of relay K^A, wire 73, common wire 36, and wires 47 and 48 back to battery R^A.

The operating mechanism of tripper arm M^A is normally energized over a first circuit which passes from battery R^A, through wires 42 and 63, circuit controller Q^A controlled by distant blade 20 of signal J^A, wires 59, 60, and 61, operating mechanism of tripper arm M^A, wires 62, 32, and 33, common wire 36, and wires 47 and 48 back to battery R^A. This circuit is closed whenever signal J^A indicates proceed, that is, when sections A-B, B-C, and C-D are all unoccupied, and under these conditions, the tripper arm occupies its in-

effective position. When a vehicle enters section A—B, however, signal J^A indicates stop, and the operating mechanism of tripper arm M^A is then energized over a second, or holding circuit, which is controlled jointly by track relay H^A and the track relay for the section to the left of point A. This circuit is not shown complete in the drawings, but a similar circuit is shown for the operating mechanism of tripper arm M^B . This latter circuit passes from battery R^A , through wires 51 and 68, back contact 38—38^b of relay H^A , wire 27, back contact 37—37^b of relay H^B , wire 72, circuit controller S^B of tripper arm M^B , wire 70, operating mechanism of tripper arm M^B , and wire 71 back to battery R^A . Returning to tripper arm M^A , the operating mechanism of tripper arm M^A is also provided with a third or pick-up circuit which is closed when signal J^A indicates caution, and when relay K^A has been picked up. This circuit passes from battery R^A , through wires 51, 52, and 53, circuit controller P^A controlled by home blade 21 of signal J^A , wires 66 and 67, front contact 54 of relay K^A , wires 55, 60, 61, operating mechanism of tripper arm M^A , wires 62, 32, and 33, common wire 36, and wires 47 and 48 back to battery R^A .

Marker light 39^A is provided with a circuit which passes from battery R^A , through wires 42 and 63, circuit controller Q^A controlled by distant blade 20, signal J^A , wire 64, marker light 39^A , wires 65 and 33, common wire 36, and wires 47 and 48 back to battery R^A . This circuit is closed whenever signal J^A indicates caution or stop.

The apparatus for each of the remaining sections is controlled by circuits similar to those described above for section A—B, as will be apparent from the drawings.

As shown in Fig. 2, sections A—B, B—C, and C—D are all unoccupied, but section D—E is occupied by a vehicle indicated diagrammatically at $\bar{W}$. Relay H^D is therefore deenergized. The circuits for both the home and distant blades of signal J^D are then open at front contacts of relay H^D , and signal J^D indicates stop. All K relays are deenergized. As a result, all circuits for the operating mechanism of tripper arm M^D are open, and the tripper arm occupies its effective position. The circuit for marker light 39^D is closed at circuit controller Q^D , and marker light 39^D is lighted.

Since section C—D is unoccupied, track relay H^C is energized, and the circuit for home blade 21 of signal J^C is therefore closed at front contact 46 of relay H^C , so that the home blade of signal J^C occupies the proceed position. The circuit for distant blade 20 of signal J^C is open at front contact 37—37^a of relay H^D , and also at circuit controller N^D , and the distant blade of signal J^C occupies the stop position. Signal J^C therefore indicates caution. All circuits for the operating mech-

anism of tripper arm M^C are open, and tripper arm M^C therefore occupies its effective position. Marker light 39^C is lighted.

Track relay H^B is energized, and the circuit for home blade 21 of signal J^B is closed at contact 46 of this relay but the circuit for distant blade 20 of signal J^B is open at circuit controller O^D . Signal J^B therefore indicates caution. Marker light 39^B is lighted, and tripper arm M^B occupies its effective position since all circuits for the operating mechanism of this tripper arm are open.

Relay H^A is energized, and both circuits for signal J^A are closed so that signal J^A indicates proceed. Marker light 39^A is therefore extinguished, and the first or normal circuit for the operating mechanism of tripper arm M^A is closed at circuit controller Q^A , so that tripper arm M^A occupies its ineffective position.

I will now assume that a following vehicle traverses the stretch of railway track shown in Fig. 2. I will also assume that this vehicle is provided with apparatus similar to that illustrated in Fig. 1, and with a part which will be engaged by the tripper arms M to give a stop indication on board the vehicle if the vehicle passes a tripper arm M which occupies its effective position. Since tripper arm M^A occupies its ineffective position, the vehicle does not receive a stop indication as it passes this tripper arm. When the vehicle enters the section A—B, track relay H^A becomes de-energized, and the operating circuits for both the home and distant blades of signal J^A are opened at front contacts of this relay, so that both the home and distant blades of signal J^A move to their stop positions, and signal J^A therefore indicates stop. When distant blade 20 of signal J^A moves to the stop position, it operates circuit controller Q^A , thereby closing the circuit for marker light 39^A , and opening the first circuit for the operating mechanism of tripper arm M^A . Marker light 39^A then becomes lighted, but tripper arm M^A does not move to its effective position, until after the vehicle has passed completely out of the section to the left of point A; for as long as the vehicle occupies section A—B and the section to the left of point A simultaneously, the second or holding circuit for the operating mechanism of tripper arm M^A is closed over a back contact 37—37^b of track relay H^A and a back contact of the track relay for the section to the left of point A, and the operating mechanism remains energized over this circuit. It will be apparent, therefore, that under the above conditions, if more than one vehicle is operated together to form a train, tripper arm M^A will remain in its ineffective position until after the last vehicle has completely entered section A—B, and the arm will not therefore engage the vehicle carried part on any of the vehicles of the train.

100

105

110

115

120

125

130

When the vehicle passes tripper arm M^B , the vehicle receives a stop indication because this arm occupies its effective position. Under some conditions of operation, this stop indication is undesirable, and the operator of the vehicle may prevent this indication by operating valve V (Fig. 1) to cause a control impulse to be transmitted from the vehicle to the trackway as the vehicle passes marker light 39^B . Assuming that the operator does this, jets of fluid issue from nozzles 11 on the train and device L^B is operated. When contact 15 of device L^B closes, relay K^B is picked up. The operation of device L^B is only momentary, and the pick-up circuit for relay K^A opens again as soon as the device returns to its normal position, but since circuit controller P^B is now closed, relay K^B is held up over its stick circuit. The pick-up circuit for the operating mechanism of tripper arm M^B is then closed, and tripper arm M^B moves to its ineffective position. The vehicle may then pass the tripper arm without receiving a stop indication.

When the vehicle enters section $B-C$, track relay H^B becomes de-energized, and the circuit for home blade 21 of signal J^B is opened so that this signal now indicates stop. At the same time, the holding circuit for the operating mechanism of tripper arm M^B is closed, and this holding circuit then functions in the manner already pointed out in connection with section $A-B$. When track relay H^A now picks up, signal J^A indicates caution, and tripper arm M^B moves to the engaging position. Marker light 39^B remains lighted.

When the vehicle enters section $C-D$, the apparatus will function in the same manner as described in connection with section $B-C$. Signal J^C then indicates stop, signal J^B moves to the caution position, and signal J^A remains in the caution position.

The operator of the vehicle cannot, however, prevent a stop indication on board the vehicle at tripper arm M^D , for if the operator transmits a control impulse to device L^D by operating valve V as the vehicle passes device L^D , relay K^D picks up, but since signal J^D indicates stop the pick-up circuit for the operating mechanism of tripper arm M^D is open at circuit controller P^D , and tripper arm M^D therefore remains in its ineffective position.

It will be observed that contact 14 of each device L is included in the operating circuits for both the home and distant blades of the adjacent signal J . With this arrangement, if a device L should, for any reason fail to occupy its normal position, so that contact 14 of the device is open, the control circuits for both the home and distant blades of the adjacent signal would be open, and the signal would indicate stop, irrespective of traffic conditions in advance of such signal. The apparatus therefore provides a check against improper operation of the relay devices L .

and prevents the possibility of a dangerous condition as a result of a failure of any of these devices to return to its normal position.

It will be apparent, therefore, that with the apparatus thus far described, the operator of a vehicle may at times control tripper arms located in the trackway by transmitting control impulses from the vehicle to the trackway as the vehicle passes predetermined points along the trackway. 75

In the form of apparatus shown in Fig. 3, the track rails 1 and 1^a are divided into track sections $X-Y$, $Y-U$, $U-T$, etc., in the usual manner, and the direction of traffic over these sections is indicated by the arrow. Each track section is provided with a track circuit similar to that shown in Fig. 2, except in this figure, the source of energy for each section is a battery 80 instead of a track transformer. 80

Section $X-Y$ is provided with a switch 81 for allowing traffic to proceed into siding 82, or to continue on the main track through section $X-Y$, depending on the position of the switch. 85

The portion of the track to the right of the fouling point Z is included in the track circuit for the section to the left of point Y in the usual and well known manner. 90

The switch 81 is operated by a motor b , which in the form here shown comprises an armature 90 and a field 93. The motor b is controlled by a polarized relay d having two contact fingers 86 and 87. The polarized relay d is of the type in which the contacts remain in the position to which they were last moved until positively moved to a different position by current in the relay winding. Motor b is further controlled by a circuit controller c operatively connected with the switch 81, and comprising a contact 85-84 closed at all times except when the switch occupies its normal position in which it is shown in the drawing. The circuit controller c also comprises a contact 85-83 closed at all times except when the switch occupies its reverse position. 100

When the switch is to be reversed, the polarity of the current supplied to relay d is reversed, so that contact fingers 86 and 87 are reversed. Current is then supplied to motor b from batteries e and f in series through wire 88, contact 86-86^a of relay d , wire 89, armature winding 90 of motor b , wire 91, contact 87-87^a of relay d , wire 92, contact 85-83 of circuit controller c , field 93 of motor b , wires 94 and 132 to battery e . When the switch reaches its full reverse position, contact 85-83 of circuit controller c opens, thereby opening the circuit just traced and so de-energizing motor b . When the switch 81 is to be returned to normal, the relative polarity 115 of the current supplied to relay d is again reversed, so that contact fingers 86 and 87 are restored to the position shown in the drawings. Current then flows from batteries e and f in series through wire 88, contact 87-87^b of 120

125

relay d , wire 91, armature winding 90 of motor b , wire 89, contact 86—86^b of relay d , wire 96, contact 85—84 of circuit controller c , field 93 of motor b , and wires 94 and 132 to battery e . As soon as the motion of switch 81 is completed, contact 85—84 of circuit controller c opens, so that the parts are restored to the positions in which they are shown in the drawings.

10 Associated with section U—T is a repeater relay h , provided with a circuit which passes from battery e , through wires 95 and 97, front contact 98 of relay H^Y , wire 99, front contact 100 of relay H^U , wire 101, front contact 102 of relay H^T , wire 103, winding of relay h , and wires 131 and 132 back to battery e . This circuit is closed only when track relays H^G , H^U , and H^T are all energized.

15 Also associated with section U—T is a slow acting relay g , and a relay device L^T of the air jet operated type previously described in connection with Fig. 1, which device is located in the trackway adjacent the entrance end of section U—T. When device L^T is operated, contact 15 of the device is closed, and slow acting relay g is then energized over a circuit which passes from a battery i , through wires 108 and 104, contact 15 of device L^T , wires 105 and 114, winding of relay g , and wires 106 and 107 back to battery i . Relay g is also provided with a stick circuit which passes from battery i , through wires 108 and 109, back contact 110 of relay h , wire 111, front contact 112 of relay g , wires 113 and 114, winding of relay g , and wires 106 and 107 back to battery i .

20 Polar relay d is governed by track relays H^Y and H^U , and also by slow acting relay g , the contacts 115 and 116 of which constitute a pole-changer to reverse the polarity of the current when relay g is energized. As shown in Fig. 3, relay g is de-energized and the circuit for relay d is from battery i , through wires 108 and 129, back contact 116—116^a of relay g , wire 118, front contact 119 of relay H^U , wire 120, front contact 121 of relay H^Y , wire 122, winding of relay d , wire 123, front contact 124 of relay H^Y , wire 125, front contact 126 of relay H^U , wires 127 and 117, back contact 115—115^a of relay g , and wires 130 and 107 back to battery i . When this circuit is closed relay d swings its contacts to the left and switch 81 occupies its normal position. When relay g is energized, the circuit for relay d passes from battery i , through wires 108 and 129, contact 116—116^b of relay g , wires 128 and 127, front contact 126 of relay H^U , wire 125, front contact 124 of relay H^Y , wire 123, winding of relay d , wire 122, front contact 121 of relay H^Y , wire 120, front contact 119 of relay H^U , wire 118, contact 115—115^b of relay g , and wires 130 and 107 back to battery i . When this circuit is closed relay d swings its contacts to the right to reverse switch 81 as described hereinbefore. It

is therefore apparent that relay d is supplied with current of one relative polarity or the other, assuming relays H^U and H^Y to be energized, depending upon whether relay g is energized or de-energized.

25 As shown in Fig. 3, sections X—Y, Y—U, and U—T are all unoccupied, relay g is de-energized, and relay d is energized in the normal direction, so that switch 81 is in position to allow traffic to continue over the switch along the main track. I will now assume that a vehicle equipped with fluid pressure jet transmitting apparatus similar to that described in Fig. 1, enters section U—T. If the engineman wishes to proceed along the main track past switch 81, he does not operate device L^T as he passes by, and the only change that occurs in the apparatus while the vehicle is in section U—T is the de-energization of relay H^T and the subsequent de-energization of relay h . As the vehicle enters section Y—U, relay H^U is de-energized, and as the vehicle enters section X—Y, relay H^Y becomes de-energized. Each of the track relays H^U and H^Y opens the circuit for relay d , and so it is impossible for relay d to be reversed and hence impossible to operate switch 81 while the vehicle is between points U and X.

30 If the engineman wishes to reverse switch 81, he operates his valve V (Fig. 1) to cause a control impulse to be transmitted from the vehicle while the vehicle is passing device L^T . The fluid pressure jets then issuing from nozzles 11 on the vehicle operate device L^T and close contact 15 of device L^T , which operation closes the pick-up circuit for relay g . Relay g therefore picks up. After the momentary operation of device L^T by the jets from the vehicle, contact 15 again closes, but since track relay H^T is now de-energized, relay h is also de-energized, and relay g is therefore held up over its stick circuit. The polarity of the current supplied to relay d is now reversed, and switch 81 is operated to its reverse position to set up the route into siding 82. When the vehicle enters section Y—U, track relay H^U is de-energized, holding the circuit for relay h open as well as opening the circuit for relay d . In similar manner, when the vehicle enters section Z—Y, track relay H^Y opens the circuit for relay d and holds the circuit for relay h open. It is apparent, therefore, that while the train is between points Z and U relay d cannot be reversed, for relay g remains energized, and the circuit for relay d is open. As soon as the vehicle passes foul point Z, however, the resultant energization of track relay H^Y completes the circuit for relay h , which then becomes energized and opens the stick circuit for relay g . Relay g then drops, supplying relay d with current of normal relative polarity, so that

switch 81 is automatically restored to its normal position.

It will be manifest, that with the apparatus described in Fig. 3, an operator on a moving vehicle may under some conditions operate a switch in advance of the vehicle by transmitting a control impulse from the vehicle to the trackway as the vehicle passes a predetermined point in the trackway, and 10 after the switch has thus been operated subsequent operation of the switch is prevented until the train has passed the switch, whereupon the switch is returned to its normal condition.

15 Referring now to Fig. 4, in the form of apparatus here illustrated, the track rails 1 and 1^a are divided into a plurality of similar track sections, only one of which, *w*—*x*, is shown complete in the drawings. Section 20 *w*—*x* is provided with a suitable source of track circuit current such as a track transformer *F^x*, the secondary 3 of which is connected across the rails adjacent the exit end of the section. The primary 4 of transformer *F^x* is reversibly supplied with alternating current through a pole-changer *v*, from an alternator *G^x* over line wires 5^a and 6^a. The pole-changer *v* may be controlled by any suitable means not shown in the drawings and may, for example, be controlled by traffic conditions in advance.

35 Section *w*—*x* is further provided with a polarized track relay *H^w*, having two windings 135 and 136. Winding 135 is constantly connected across the rails adjacent the entrance end of the section, and winding 136 is constantly supplied with alternating current from any suitable source not shown in the drawings.

40 Located adjacent the entrance end of section *w*—*x* and controlled by track relay *H^w*, is a semaphore signal *y*, capable of indicating proceed, caution or stop. When pole-changer *v* occupies the position shown in the drawings relay *H^w* is energized in the normal direction, in which it is shown in the drawings; and signal *y* indicates proceed, current being supplied to the signal over a circuit which passes from a battery *s*, through wire 45 137, contact 138—138^a of relay *H^w*, wire 139, operating mechanism of signal *y*, and wire 140 back to battery *s*. When pole-changer *v* is reversed, however, relay *H^w* is energized in the reverse direction, contact 138—138^b of relay *H^w* is closed, and the circuit for the signal then passes from battery *s* through wire 55 137, contact 138—138^b of relay *H^w*, wire 141, operating mechanism of signal *y* and wire 140 back to battery *s*. Under these conditions signal *y* indicates caution. When relay *H^w* is de-energized, both of the above circuits are open, and signal *y* indicates stop.

60 Located in the trackway a little in rear of point *w* is an upwardly extending pipe 142 terminating in a nozzle 143. Pipe 142 is at

times supplied with fluid pressure, through a valve *p*. The valve *p* comprises a valve stem 144 provided with an armature 145 and a winding 146. When winding 146 is de-energized, the valve stem 144 is moved to its upper or normal position by a spring 147. Under these conditions the pipe 144 is connected with a source of fluid pressure not shown in the drawings, so that a jet of the fluid issues from nozzle 143. When winding 146 is energized, however, the valve stem is moved downwardly against the bias exerted by spring 147 and the pipe 144 is disconnected from the source of fluid pressure, so that no fluid issues from nozzle 143. The supply of energy to winding 146 is controlled by a circuit controller *z* operated by signal *y*. When signal *y* indicates proceed, circuit controller *z* is closed, and current then flows from battery *s* through wire 148, circuit controller *z*, wire 149, winding 146, and wire 150 back to battery *s*. When signal *y* indicates caution, or stop, the circuit just traced is open at circuit controller *z*. It is manifest, therefore, that a jet of fluid will issue from nozzle 143 at all times except when signal *y* indicates proceed.

65 As shown in Fig. 4, the section to the left of point *w* is occupied by a vehicle designated in general by the reference character *q*. The vehicle *q* is provided with a relay device *L^a*, similar to the device *L* described in connection with Fig. 1. The device *L^a* is located in such position with respect to the vehicle, that as the vehicle passes the nozzle 143 in the trackway, a jet of fluid issuing from the nozzle will strike diaphragm 13 and operate contact 14 of the device *L*. The vehicle *q* is also provided with a stick relay *r* and a normally open manually controlled switch *t*. When switch *t* is closed, a pick-up circuit is closed for relay *r*, and current flows from a battery 151, through wires 152 and 153, switch *t*, wires 154 and 155, winding of relay *r*, and wire 156 back to battery 151. Relay *r* is also provided with a stick circuit which passes from battery 151, through wires 157 and 158, contact 14 of device *L*, wire 159, front contact 160 of relay *r*, wires 161 and 155, winding of relay *r*, and wire 156 back to battery 151. After relay *r* has once been picked up by operation of switch *t* the stick circuit just traced holds the relay energized until device *L^a* is operated.

65 In explaining the operation of the appa-

ratus shown in Fig. 4, I will first assume that relay r is energized over its stick circuit, and that signal y indicates proceed as shown in the drawings. Under these conditions, no fluid issues from nozzle 143, and if the vehicle g passes the nozzle 143, the vehicle-carried apparatus is unaffected.

I will now assume that signal y indicates caution or stop. Under these conditions valve 10 p is de-energized, and a jet of fluid issues constantly from nozzle 143. If the vehicle g passes nozzle 143 under these conditions device L^a is operated to open contact 14. As a result, the stick circuit for relay r is opened, 15 so that valve E. P. V. is de-energized and the brakes are applied on the vehicle g . Before the brakes can be released, the operator of the vehicle must close switch t , which is usually located in such position on the vehicle that 20 the operator has to leave his cab to operate the switch.

Under some conditions of operation, it may be desirable to pass the nozzle 143 without receiving an application of the brakes even 25 though a jet of fluid is issuing from nozzle 143. This may be accomplished by closing a manually controlled switch u , which is connected in multiple with contact 14 of device L^a . When switch u is closed, contact 14 of 30 device L^a is shunted, and if contact 14 is then opened, the circuit for relay r is still closed at switch u . Under these conditions therefore no brake application is incurred on the vehicle.

35 Although I have herein shown and described only a few forms of railway traffic controlling apparatus embodying my invention, it is understood that various changes and modifications may be made therein within the scope of the appended claims without departing from the spirit and scope of my invention.

Having thus described my invention what I claim is:

45 1. Railway traffic controlling apparatus, comprising a relay device, and a nozzle, one of which is located in the trackway and the other mounted on a vehicle, means for at times supplying fluid to said nozzle for causing a jet of the fluid to issue from the nozzle to operate said device, and traffic governing means controlled by said device.

50 2. Railway traffic controlling apparatus, comprising a relay device, and a nozzle, one of which is movable with respect to the other, means for at times supplying fluid to said nozzle for causing a jet of the fluid to issue from the nozzle to operate said device, and traffic governing means controlled by said device.

55 3. In combination, a nozzle, means for at times supplying fluid to said nozzle to cause a jet of the fluid to issue from the nozzle, a relay device movable with respect to said nozzle and responsive to said jet, and rail-

way traffic controlling apparatus controlled by said device.

4. In combination, a relay device, a nozzle, means for at times supplying said nozzle with fluid for causing a jet of the fluid to issue from the nozzle to operate said device, and railway traffic controlling apparatus controlled by said device.

5. In combination with a stretch of railway track, a nozzle located on a vehicle, means for at times causing a jet of fluid to issue from said nozzle, and traffic governing apparatus in the trackway controlled by said jet.

6. In combination, a main reservoir on a vehicle, means for supplying fluid under pressure to said reservoir, an auxiliary reservoir connected with said main reservoir through a restricted orifice, a normally closed manually controlled valve, a plurality of nozzles, means including said valve for connecting said nozzles with said auxiliary reservoir in such manner that when said valve is open a jet of the fluid issues from each of the nozzles, a relay device located in the trackway and operable by said jets of fluid, and traffic governing apparatus controlled by said device.

7. Railway traffic controlling apparatus comprising a section of railway track, a tripper arm for said section, means located in the trackway for normally controlling said arm in accordance with traffic conditions, and means located partly in the trackway and partly on a vehicle for at times controlling said arm from the vehicle.

8. Railway traffic controlling apparatus, comprising a plurality of successive track sections, a tripper arm for each section biased to an effective position, trackway means for normally causing each such arm to occupy its ineffective position when the two sections next in advance are unoccupied, and manually controlled means on a vehicle co-operating with said trackway means for at times causing each such tripper arm to occupy its ineffective position if the second section in advance is occupied but not if the first section in advance is occupied.

9. Railway traffic controlling apparatus comprising a section of railway track, a tripper arm for said section, means located in the trackway for normally controlling said arm in accordance with traffic conditions, manually controlled means on a vehicle for at times transmitting a jet of fluid from the vehicle to the trackway, and a relay device in the trackway responsive to such jet for controlling said tripper arm.

10. Railway traffic controlling apparatus, comprising a plurality of successive sections of railway track, a tripper arm for each section arranged to occupy an effective or an ineffective position, means for holding each such arm in its ineffective position when and only when the two sections next in advance

are unoccupied, means on the vehicle for transmitting control impulses to the trackway, and a relay device for each section responsive to said control impulses for at times energizing each such arm when the second section in advance is unoccupied.

11. In combination, a stretch of railway track comprising a plurality of successive track sections, a tripper arm for each section having an effective and an ineffective position, controlling means in the trackway for causing each such arm to occupy its ineffective position when the two sections next in advance are unoccupied, means on a vehicle for at times transmitting a jet of fluid from the vehicle to the trackway, and means in the trackway responsive to said jet for at times causing each such arm to occupy its ineffective position when the first section in advance is unoccupied but not when the associated section is occupied.

12. In combination, a stretch of railway track comprising a plurality of successive track sections, a tripper arm for each section having an effective and an ineffective position, controlling means in the trackway for causing each such arm to occupy its ineffective position when the two sections next in advance are unoccupied, means on a vehicle for at times transmitting a jet of fluid from the vehicle to the trackway, and a relay device for each section responsive to said jet for at times causing each such arm to occupy its ineffective position when the first section in advance is unoccupied but the second section in advance is occupied.

13. Railway traffic controlling apparatus comprising a plurality of successive track sections, a track circuit for each section including a track relay, a signal for each section controlled in part by the associated track relay, a tripper arm for each section normally controlled by the associated signal, means on a vehicle for transmitting a control impulse from the vehicle to the trackway, a relay device for each section responsive to said control impulse, and means controlled by each such device for at times controlling the associated tripper arm.

14. In combination, a stretch of railway track comprising a plurality of track sections, a track circuit for each section including a track relay, a signal for each section, controlling means for each signal including the associated track relay and so arranged that each signal normally indicates proceed but that when a section is occupied the corresponding signal indicates stop and the first and second signals in the rear thereof indicate caution, a tripper arm associated with each signal and arranged to occupy an effective position when the signal indicates caution or stop but to occupy an ineffective position when the signal indicates proceed, means on a vehicle for transmitting a control

impulse from the vehicle to the trackway and a trackway device for each section set into operation by a control impulse to cause the associated tripper arm to occupy its ineffective position provided the associated signal indicates caution.

15. In combination, a stretch of railway track, a tripper arm located in the trackway and biased to an effective position, means for moving said arm to an ineffective position when traffic conditions in advance are safe, a relay device located in rear of said arm and responsive to a jet of fluid for at times causing said arm to move to its ineffective position although traffic conditions in advance are dangerous, means on a vehicle for projecting a jet of fluid toward said device, and means in the trackway for holding said arm in its ineffective position until the vehicle has passed the arm if the arm is in its ineffective position when the vehicle approaches the arm.

16. Railway traffic controlling apparatus comprising a movable diaphragm located in the trackway, a contact controlled by said diaphragm, manually operable means on a vehicle for directing a jet of fluid into the trackway to operate said diaphragm, a relay in the trackway, means controlled by said contact for at times energizing said relay, means for subsequently holding said relay energized independently of said contact, and a traffic governing device controlled by said relay.

17. In combination, a stretch of railway track comprising a plurality of successive track sections, a track circuit for each section including a track relay, a signal for each section, controlling means for each signal including the associated track relay and so arranged that each signal normally indicates proceed but that when a section is occupied the corresponding signal indicates stop and the first and second signals in rear thereof indicate caution, a relay device for each section responsive to a jet of fluid to operate its contacts, an auxiliary relay for each section controlled by the associated relay device, a first circuit controller for each section arranged to be closed when the signal indicates caution, a tripper arm for each section biased to an effective position but occupying an ineffective position when energized, a circuit for each said arm controlled by the auxiliary relay and said first circuit controller, a second circuit controller for each section arranged to be closed when the associated tripper arm occupies its ineffective position; a holding circuit for each said arm controlled by a front contact of the track relay for the associated section, the associated said second circuit controller, and a front contact of the track relay for the section next in rear; a third circuit controller for each section arranged to be closed when the signal for the

section indicates proceed, a circuit for said tripper arm including said third circuit controller, and manually controlled means on a vehicle for transmitting a jet of fluid to the trackway to operate said relay device.

18. In combination, a stretch of railway track, a relay device for said stretch comprising a diaphragm biased to a normal position, means on a vehicle for actuating said diaphragm, a first contact for said stretch arranged to be opened except when said diaphragm occupies its normal position, a signal for said stretch, operating circuits for said signal controlled by said contact and by traffic conditions in advance, a second contact arranged to be closed when said diaphragm is actuated, and a traffic governing device controlled by said signal and said second contact.

19. In combination, a stretch of railway track comprising a plurality of successive track sections, a signal for each track section, a control circuit for each signal arranged in such manner that each signal normally indicates proceed but that when a section is occupied the corresponding signal indicates stop and the first and second signals in the rear thereof indicate caution, a relay device for each section comprising a movable diaphragm biased to a normal position, manually controlled means on a vehicle for actuating said diaphragms, a first contact for each section controlled by the diaphragm of the associated relay device and arranged to be closed when the diaphragm is actuated, traffic governing apparatus for each section controlled by the first contact of the associated relay device, and a second contact on each relay device interposed in the control circuit for the adjacent signal and arranged to be closed only when the diaphragm occupies its normal position.

20. Railway traffic controlling apparatus comprising a plurality of successive track sections, a track circuit for each section including a track relay, a signal for each section controlled in part by the associated track relay, a tripper arm for each section normally controlled by the associated signal, means on a vehicle for transmitting a control impulse from the vehicle to the trackway, a relay device for each section responsive to said control impulse, means controlled by each such device for at times controlling the associated tripper arm, a marker light associated with each tripper arm for indicating the location of the tripper arm, and means controlled by each signal for controlling the associated marker light.

21. In combination, a stretch of railway track comprising a plurality of track sections, a track circuit for each track section including a track relay, a signal for each section, controlling means for each signal including the associated track relay and so

arranged that each signal normally indicates proceed but that when a section is occupied the corresponding signal indicates stop and the first and second signals in the rear thereof indicate caution, a tripper arm associated with each signal and arranged to occupy an effective position when the signal indicates caution or stop but to occupy an ineffective position when the signal indicates proceed,

means on a vehicle for transmitting a control impulse from the vehicle to the trackway, a trackway device for each section set into operation by a control impulse to cause the associated tripper arm to occupy its ineffective position provided the associated signal indicates caution, a marker light associated with each tripper arm for indicating the location of the tripper arm, and a circuit for each marker light controlled by the associated signal and arranged to be closed only when the associated signal indicates caution or stop.

22. In combination with a stretch of railway track, a nozzle located in the trackway, means for at times causing a jet of fluid to issue from said nozzle, and governing apparatus on a vehicle controlled by said jet of fluid.

23. Railway traffic controlling apparatus comprising a stretch of railway track provided with a switch, a relay device responsive to a jet of fluid for controlling said switch, and vehicle carried means for transmitting a jet of fluid from the vehicle to the trackway to operate said device.

24. Railway traffic controlling apparatus, comprising a stretch of railway track provided with a switch, a relay device located in the trackway, means including said device for operating said switch, means including a track rail circuit for preventing subsequent operation of said switch while a vehicle is between said trackway device and the switch, and vehicle carried means for transmitting a jet of fluid from the vehicle to the trackway to operate said device from the vehicle.

25. In combination, a stretch of railway track provided with a switch, a track relay for said stretch, a repeater relay controlled by said track relay, a relay device arranged to respond to a jet of fluid, a slow acting relay controlled by said relay device and said repeater relay, a polarized relay controlled by said slow acting relay, means controlled by said polarized relay for operating said switch, and means on a vehicle for projecting a jet of fluid toward said relay device to operate said relay device.

26. In combination, a first, a second, and a third sections of railway track, a switch for the third section, a track relay for each section, a repeater relay controlled by a front contact of each track relay, a relay device arranged to be operated by a jet of fluid, a slow acting relay controlled by said device and a back

- contact of said repeater relay, a polarized relay controlled by the track relay for the second and third sections and the slow acting relay, means controlled by said polarized relay for actuating said switch, and means on a vehicle for projecting a jet of fluid toward said relay device.
27. In combination, a first, a second, and a third sections of railway track, a switch for the third section capable of assuming two extreme positions, operating mechanism for moving the switch to one or the other of such extreme positions in accordance with the relative polarity of the energy supplied to such mechanism, a polarized relay for controlling the polarity of the energy supplied to such mechanism, a track circuit for each section including a track relay, a repeater relay controlled by a front contact of each track relay, a relay device located in the trackway and responsive to a jet of fluid for operating its contacts, a slow acting relay, a pick-up circuit for said slow acting relay including a contact of said device, a stick circuit for said slow acting relay including a back contact of said repeater relay, means controlled by said slow acting relay for supplying said polarized relay with current of one relative polarity or the other, and means on a vehicle for projecting a jet of fluid from the vehicle to said device to operate said device as the vehicle passes said device.
28. In combination, a stretch of railway track provided with a switch capable of assuming two extreme positions, means located in the trackway for normally causing said switch to occupy one extreme position, means on a vehicle for projecting a jet of fluid toward the trackway, and a relay device in the trackway responsive to said jet for at times causing said switch to occupy the other extreme position.
29. In combination, a stretch of railway track provided with a switch, means located in the trackway for actuating said switch, a relay device responsive to a jet of fluid for controlling said trackway means, and means located on a vehicle for at times directing a jet of fluid toward the trackway to actuate said device.
30. In combination, a stretch of railway track, a nozzle located in the trackway, means for at times causing a jet of fluid to issue from said nozzle, and train carried governing means controlled by said jet of fluid.
31. In combination, train carried apparatus comprising a stick relay, a pick-up circuit for said relay including a normally open manually controlled switch, a relay device responsive to a jet of fluid for operating its contacts, a stick circuit for said stick relay including a contact of said device, and traffic governing means controlled by said stick relay.
32. In combination, a stretch of railway

track, a nozzle in the trackway, means located in the trackway and controlled by traffic conditions for at times causing a jet of fluid to issue from said nozzle, and governing means on a vehicle controlled by said jet.

33. In combination, a stretch of railway track, a signal for said stretch controlled by traffic conditions, a nozzle in the trackway, means located in the trackway and controlled by said signal for at times causing a jet of air to issue from said nozzle, a relay device on a vehicle controlled by said jet, and governing means on the vehicle controlled by said relay device.

34. In combination, a vehicle carried relay device responsive to a jet of air to operate its contacts, traffic governing means on the vehicle normally controlled by said device, a manually controlled switch for at times modifying the control of said governing means by said device, and means located in the trackway for at times projecting a jet of fluid toward said device to operate said device.

35. Railway traffic controlling apparatus comprising means in the trackway for directing a jet of fluid toward a passing vehicle, apparatus on the vehicle responsive to said jet, governing means on the vehicle controlled by said apparatus, and manually operable means on the train for at times modifying the control of said vehicle governing means by said apparatus.

36. In combination with a stretch of railway track, a nozzle located in the trackway, means controlled by traffic conditions for supplying fluid to said nozzle to cause a jet of fluid to issue from the nozzle, a relay device on a vehicle responsive to fluid from said jet, and governing means on the vehicle controlled by said device.

In testimony whereof I affix my signature.
RONALD A. McCANN.
